FUSIBLE PLUG FOR STEAM BOILERS

Luther D. Lovekin, Villa Nova, Pa.

Application June 10, 1930. Serial No. 460,164

10 Claims. (Cl. 122—504.3)

My invention relates to a fusible plug for insertion in the crown sheet or the like or in the tubes of boilers, usually as a low water safety blow-off, one end of the plug being presented 5 into the interior of a boiler and the other into the furnace heating the boiler.

A purpose of my invention is to provide a fusible plug of the character indicated that is easy and inexpensive to manufacture and well 10 suited to the needs of service.

A further purpose is to protect the fire end of the fusible core of a plug of the character indicated with a packing adapted to prevent contact between the hot furnace gases and the end surface of the fusible core and to blow out ahead of the core when the core fuses with boiler pressure back of the core.

A further purpose is to shield the end of the fusible core that is presented to the interior of 20 a boiler from contact with the water of the boiler by means of an impervious coating non-reactive with the water of the boiler and desirably of metal, such as copper, tin, nickel, Monel metal or the like applied by blow-pipe, electrolytically, or as thin sheets, insufficiently strong 25 to withstand the steam pressure unless supported against rupture by the fuse element.

A further purpose is to provide a composite 30 fuse plug of the character indicated with an outer non-fusible body well suited to mount the fusible core, a protective packing at the fire end of the fusible core and a metallic sheet at the water end thereof.

Further purposes will appear in the specification 35 and in the claims.

I have elected to illustrate a few only of the many different forms of my invention, selecting forms that are practical and efficient in operation and which well illustrate the principles involved.

Figure 1 is a fragmentary vertical section showing a plug embodying one form of my invention.

Figures 2 to 8 are fragmentary views corresponding generally to Figure 1 but showing different forms.

Like numerals refer to like parts in all figures.

In the past fusible plugs of the character indicated have sometimes failed to operate because of chemical or physical changes in the fusible 50 material, changes that have unduly raised the fusing temperatures.

It has been found that these changes have been sometimes incident to the hot furnace gases engaging the fusible core at its lower end, sometimes 55 to engagement between the upper end of the

fusible core and water within the boiler, and sometimes to both of these factors.

A purpose of my invention is to avoid danger of the plug not operating from either or both of these causes.

I protect the lower end of the plug that is presented toward the fire with a packing, desirably of sheet asbestos or the like, that is unable to hold its place within the non-fusible body of the plug against the boiler pressure coming 60 against it when the fuse element of the plug melts but does provide the fuse element with sufficient protection from the hot gases within the furnace to avoid any danger of a deleterious chemical or physical reaction between the fuse material of the 65 plug and the hot gases within the furnace.

I also provide a thin metal seal, desirably of copper, tin, nickel, Monel metal or the like, between the water within the boiler and the upper 70 end of the plug.

In the form shown in Figure 1 the plug body 10, desirably of brass or the like externally threads at 11 into a crown sheet 12 or the like of any boiler.

The body 10 is perforated longitudinally, an 80 upper portion 13 of the perforation tapering downwardly from the top and a lower portion 14 thereof having a plurality of parallel grooves 15.

I fill the lower or fire end portion of the plug with packing which may comprise sheets of asbestos cardboard 16 fitting the grooves and desirably 85 also the spaces intermediate the grooves.

I place the fusible element 17 in the upwardly flaring portion 13 of the perforation.

While the form shown in Figure 1 provides 90 ample protection from chemical or physical action between the material of the plug and hot gases within the furnace it does not avoid danger of deterioration incident to chemical or physical action between the plug and the water within the 95 boiler.

In Figures 2 to 8 I illustrate different and alternative connections between the non-fusible body 10 and the fusible core 17, showing the same seal 16 of asbestos material or the like at the fire end 100 of the body between the fuse element and the hot gases of the furnace, and also different forms of my metal shield between the fuse element and the water within the boiler.

In Figure 2 the fuse element 17' is an upwardly 105 hollowed truncated cone fitting loosely in the upwardly diverging conical seat 13' presented by the body 10' and presents a circumferential upper surface against the bottom of a thin sheet 18 of copper or the like that is screw clamped circum-

ferentially at 26 against the upper end of the body 10'.

The fusible core 17' is shown spaced somewhat above the packing 16 and while upwardly hollowed from its upper surface presents sufficient support to the bottom of the metal sheet 18 to let this sheet safely support the boiler pressure.

If the core 17' fuses, as incident to abnormally low water in the boiler, the sealing sheet 18 is no longer adequately supported and ruptures under the boiler pressure, which then drives the fuse element and packing into the fire.

In the form shown in Figure 3 a longitudinally hollow fuse element 17² includes a lower portion threading into the body 10² and an upwardly extending stem that flares at the top to present a flat supporting surface against a major portion of the bottom of the sealing sheet 18¹, the stem being spaced radially inwardly from the interior of the bore of the body 10².

The upward hollowing of the fuse element of Figure 2, and the longitudinal perforation and inward space from the interior of the body of the element of Figure 3 secures at fusion of the element a desirable instant collapse of the support given by the fuse element to the sealing sheet and also desirably reduces the quantity of fuse material for each plug.

In Figure 4 the fuse element 17³ is adapted to be inserted from the bottom of the metal body member 10³ before the insertion of the packing 16 and presents an upwardly extending stem 19 to engage the central portion of the bottom of the sheet metal seal 18² which may be soldered at 20 around its outside circumference to the plug member 10³.

The form shown in Figure 5 is very similar to that shown in Figure 3 except that the sheet metal shield 18³ is mounted in a bushing member 21 being desirably soldered at 20' into the upwardly directed counterbore 22 of the bushing.

The bushing 21 is threaded at 23 into the internally threaded upper end of the body member 10⁴, packing 24 being desirably provided to prevent danger of leakage from the boiler into the interior of the body member.

The form shown in Figure 6 is generally like that shown in Figure 1 with the exception that I have provided the top of the body 10⁵ in the upper end of the fuse element 17⁵ with a metallic coating 18⁴ that may be deposited by a blow gun, electrolytically or otherwise.

The metallic coating should adhere so closely to the metal of the plug body as to insure against leakage of the water into the space within the body.

The form shown in Figure 7 is generally like that of Figure 6 except that the plug is inserted from below the crown seat instead of from above.

The form shown in Figure 8 is like that shown in Figure 6 except that I have provided a different connection between the fusible element 17⁷ and the non-fusible body 10⁷, in that instead of upwardly tapering the body I have provided a succession of parallel grooves 25 that may desirably have a diameter slightly greater than the corresponding grooves 14 seating the asbestos packing 15 in the lower portion of the body.

It will be seen that in all the forms I have provided an effective shield between the lower end of the fuse element and the hot gases within the furnace; that in all the forms except the first form I have provided a metallic seal between the water of the boiler and the upper end of the fusible element, the illustrated differ-

ences being differed with respect to the connection between the plug body and the fuse material, with respect to the connection between the fuse element and sealing plate at the upper end of the fuse element, and with respect to the form of the fuse element.

In Figures 2 to 5 I have illustrated that the fuse element may desirably be hollow; that it may desirably present an enlargement to the sealing sheet 18; that it may longitudinally interlock with the body near the lower end thereof in threads or parallel grooves, and extend upwardly without filling the interior of the body and desirably flare to present adequate support for the bottom of the sealing plate.

Figures 6, 7 and 8 illustrate that the metal coating which seals the end of the fusible element from the water of the boiler may comprise merely a film of metal such as is readily deposited by means of a blow pipe or electrolytically.

In all the forms shown the sealing sheet is no longer able to withstand the boiler pressure when the fusible core fuses, the boiler pressure blowing the fused core and packing out into the fire in the usual way as soon as the fuse element collapses, usually incident to dangerously low water in the boiler.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a fuse plug of the character indicated, a non-fusible body having a longitudinal perforation, packing of heat insulating refractory across the fire end of the perforation, a fusible core at the other end of the perforation having a rigid connection with the body normally supporting it from movement toward the fire end of the perforation, and a sheet of metal sealing the core from the water of the boiler.

2. A non-fusible body of the character indicated having a longitudinal perforation, a packing therein of poor heat conductivity at the fire end thereof, a fusible core at the other end of the perforation and a deposited metallic seal between the water and the core.

3. A non-fusible body of the character indicated having a longitudinal perforation, a packing therein of poor heat conductivity at the fire end thereof, a fusible core in the perforation connected to the body toward its fire end and spaced from the body for a portion of its length thereabove, and a thin metal sheet normally supported across the perforation for a portion of the sectional area thereof by the top of the core and fastened to the body.

4. A non-fusible body of the character indicated having a longitudinal perforation, a packing therein of poor heat conductivity at the fire end thereof, a fusible core in the perforation connected to the body toward its fire end and spaced from the body for a portion of its length thereabove, a thin metal sheet normally supported across the perforation for a portion of the sectional area thereof by the top of the core and circumferentially clamped to the body.

5. A non-fusible body of the character indicated having a longitudinal perforation, parallel

- grooves at right angles to the axis of the body near the fire end of the perforation, sheets of asbestos or the like across the perforation in the grooves, and a fusible core connected to the interior of the plug above the packing. 5
6. A non-fusible body of the character indicated having a longitudinal perforation, parallel grooves near the fire end of the perforation, sheets of asbestos or the like across the perforation in the grooves, a fusible core threaded into the body and extending upwardly from its thread connection with the body and a metal sealing sheet sealing to the body across the perforation and normally supported across the perforation by the top of the core. 10
7. A non-fusible body of the character indicated having a longitudinal perforation, parallel grooves near the fire end of the perforation, sheets of asbestos or the like across the perforation in the grooves, a fusible core threaded into the body and extending upwardly from its thread connection with the body and a metal sealing sheet sealing to the body across the perforation and normally supported across the perforation by the top of the core, said core being hollow for a portion of its length. 15
8. A non-fusible body having a longitudinal perforation and parallel grooves near the fire end 20

- of the perforation and having the water end of the perforation counterbored, packing in the fire end of the perforation, a metal sheet fitting the counterbore and fastened circumferentially to the body sealing the outside of the body from the interior bore and a fusible element intermediate the body and packing, connected to and supported by the body, the said sheet being normally supported by the upper end of the core to an extent adequate to prevent rupture incident to the boiler pressure and the sheet being too weak to prevent rupture when the core collapses in fusion. 80
9. A body having a longitudinal perforation and parallel grooves at intervals along the perforation, packing in the fire end of the perforation, a fusible element in the water end of the perforation and a metal coating deposited on the top of the fusible element and of the plug body. 90
10. A fusible plug element adapted for use in water pressure locations exposed also to fire, comprising a hollow threaded member having the threaded end adapted for exposure to the heat, a heat insulation filling the end of the plug at the threaded end, a fusible member in the opposite end of the hollow member and a film protection for the fusible element. 95
